UNITED STATES PATENT OFFICE.

FRIDITHJOF W. ANDERSON, OF EAU CLAIRE, WISCONSIN, AND CHARLES H. ORDAS, OF CHICAGO, ILLINOIS.

COOLING DEVICE FOR INTERNAL-COMBUSTION ENGINES.

Application filed January 20, 1926. Serial No. 82,543.

This invention relates to cooling devices for internal combustion motors, and the said invention has particular reference to the cooling of water used in tanks in which internal combustion engines may be submerged, or in association with which they may be installed, to be cooled by the volume of water without employing water circulating mechanism such as pumps or especially constructed thermosiphoning apparatus.

It is an object of this invention to provide means for directing air to the interior of water tanks of the character indicated when employed on moving equipment such as trucks, railway cars or vehicles.

Primarily, this invention is of importance when used in connection with power plants or engines installed for driving what are known as section motor cars, and in this invention, provision is made for increasing or diminishing the air delivered to the tank, or for closing the mouth of the tank when that is desirable, as it may be in cold weather.

It is a further object of this invention to provide novel means for retaining air deflecting means in different positions of adjustment so that a greater or less degree of air deflection to the interior of the tank may result, according to the speed of the car, the velocity of the wind, or the like.

With the foregoing and other objects in view, the invention consists in the details of construction, and in the arrangement and combination of parts to be hereinafter more fully set forth and claimed.

In describing the invention in detail, reference will be had to the accompanying drawings forming part of this application wherein like characters denote corresponding parts in the several views, and in which—

Figure 1 illustrates a view in elevation of a fragment of an equipment showing a tank with a mouth and a device embodying the invention applied thereto;

Figure 2 illustrates an enlarged detailed sectional view of the tank and a device embodying the invention applied thereto; and

Figure 3 illustrates a sectional view of the device on a line 3—3 of Fig. 2.

In these drawings, 5 denotes a tank of conventional form having a bowl-shaped mouth or spout 6 secured thereon communicating with the interior of the tank. The aforesaid parts may be secured together

through the employment of fastenings 7 which may consist of studs rising from the tank and projecting through apertures of the flange of the spout, or bolts of suitable type may be employed.

A deflector 8 having a concave face 9 is adjustably mounted in the spout, the said deflector having apertured bosses 10 and 11 opposite each other in order that the deflector may be pivotally mounted in the mouth of the spout. Pivots 12 and 13 have their ends anchored in the bosses 10 and 11, and, in the present embodiment of the invention, the joint is shown as screw threaded. The outer end of the pivot 13 is threaded to engage a nut 14 by which the parts are held in assembled relation, whereas the pivot 12 is elongated, as compared with the pivot 13, and it is provided with threads to engage a nut 15. A spring 16 encircles the pivot 12 between the nut and the outer surface of the bowl, and through the adjustment of the nut 15, the tension of the spring may be increased or diminished in order that pressure on the contacting surfaces of the operating parts may be increased or diminished for regulating the friction, a condition which will insure that the deflector will be held in different positions of adjustment by said frictional engagement.

The relation of parts is such, in the present embodiment of the invention, that the deflector will act as a cover when it is adjusted to an approximately horizontal position, and such adjustment is made when it is desired to exclude air from the interior of the tank. Such condition may be desirable in cold weather and certainly until the engine developed a temperature which would heat the contents of the tank.

It will be apparent from an inspection of the drawings that the deflector may be set in an approximately horizontal position, or at other angles with relation thereto, and that by reason of the adjustment, the air collected and deflected during the travel of the car may be regulated.

We claim:—

1. In a cooling device for internal combustion engines a tank having an opening, a bowl-like mouth on the tank having an opening registering with the opening in the tank, pivots extending horizontally at the upper edge of the mouth, a deflector mounted

thereon, the said deflector being concave and of a size to close the said mouth when in horizontal position and extending approximately equidistantly above and below the mouth when in vertical position.

2. In a cooling device for internal combustion engines, a tank having an opening, a bowl-like mouth on the tank having an opening registering with the opening in the 10 tank, pivots extending horizontally at the upper edge of the mouth, a deflector mounted thereon, the said deflector being concave and of a size to close the said mouth when in horizontal position and extending approximately 15 equidistantly above and below the mouth when in vertical position, and a friction means for holding the deflector in different positions.

3. In a cooling device for internal combustion engines, a tank having an opening, 20 a deflector in the opening, the said deflector

being concave and of a size to close said opening when in horizontal position, and means for pivotally mounting the deflector on the tank with relation to said opening for 25 positioning the deflector to extend approximately equidistantly above and below the top of the opening when in vertical position.

4. In a cooling device for internal combustion engines, a tank having an opening, 30 a deflector in the opening, the said deflector being concave and of a size to close said opening when in horizontal position, means for pivotally mounting the deflector on the tank with relation to said opening for 35 positioning the deflector to extend approximately equidistantly above and below the opening when in vertical position, and means for holding the deflector in different positions of adjustment.
